REGULATING GATE

James H. Fitzgerald, Westfield, N. J.

Application March 7, 1939, Serial No. 260,382

3 Claims. (Cl. 221—144)

This invention relates to regulating gates.

The regulating gate disclosed herein is adapted for association with such devices as bottom dump buckets, concrete hoist towers, sludge and sewage bins, cement bins, or other containers of materials to be discharged therefrom, the regulating gate acting as a closure valve for the bottom discharge of the container.

The discharge at the lower end of, for instance, a bottom dump bucket has heretofore been closed by a regulating gate functioning as a closure valve and such gates have generally been of a clamshell type embodying a pair of closure doors or members of arcuate formation that have their concaved sides disposed upwardly and upon which the material in the hopper or bucket is supported. In such devices the weight of the material ranges from 4,000 pounds to 32,000 pounds, and it will be readily seen that such weights bearing on gates of the clamshell type have a tendency to open the gates as well as resisting closure of the gates.

It is therefore the primary object of the present invention to provide a regulating gate for apparatus of the foregoing character wherein the weight of the materials being delivered into the bucket, hopper or container acts upon the gate to assist closing movements thereof as well as acting to hold the gates in their closed position, but being of such construction as to permit relatively easy opening movements of the gate when it is desired to discharge the contents of the bucket, hopper or other container.

More specifically, an object of this invention is to provide a regulating gate for a bottom dump bucket or other container wherein the gate comprises a pair of arcuate valves or gate members for controlling the flow of materials through the bucket with the convex sides of the gate members disposed upwardly and having their journaled mountings relatively disposed so as to cause the adjacent edges of the gate members to move in generally downward directions toward each other to their meeting closed positions relative to the discharge at the bottom of the bucket so that the weight of the material in the bucket will aid in the closing of the regulating gates as well as acting to maintain the regulating gates in their closed positions.

With the above and other objects in view that will become apparent as the nature of the invention is better understood, the same consists in general of certain novel details of construction and combination of parts hereinafter more fully

described, illustrated in the accompanying drawings, and specifically claimed.

In the drawings:

Fig. 1 is a top plan view of a bottom dump bucket constructed in accordance with the present invention, the housing for the operating gears for the regulating gate being shown in section,

Fig. 2 is a vertical longitudinal sectional view taken on line 2—2 of Fig. 1, showing the regulating gates to be of substantially semi-cylindrical formation with the convex sides thereof disposed upwardly and facing the discharge opening in the bottom of the bucket, the regulating gates being shown in their closed positions,

Fig. 3 is a vertical longitudinal sectional view, similar to Fig. 2, with the regulating gates in their fully opened positions,

Fig. 4 is a vertical longitudinal sectional view, similar to Fig. 2, showing another form of regulating gate with the gate sections formed of arcuate segments less than 180° and so disposed as to support the material in the bucket entirely thereabove.

Fig. 5 is a side elevational view, partly broken away, of a bottom dump bucket or the like with the modified construction of operating means for the regulating gate sections,

Fig. 6 is a vertical cross sectional view taken on line 6—6 of Fig. 5, showing the regulated gates of segmental formation with gear connections therebetween and a pinion drive for the geared connections,

Fig. 7 is a horizontal sectional view taken on line 7—7 of Fig. 6, and

Fig. 8 is a fragmentary vertical sectional view at right angles to the showing in Fig. 6.

Referring more in detail to the accompanying drawings and particularly to Figures 1 to 3, the showing in said figures may be illustrative of a concrete hoist tower, sludge or sewage bin, cement bin, or other container, but for the purposes of clarity in the description, the device will be referred to as a bottom dump bucket designated by the reference character 10 and while the same is illustrated in Figure 1 as being of rectangular formation, the same may be of any shape desired. The bottom dump bucket 10 includes side walls 11 and end walls 12 and a pair of inclined boards 13 extending inwardly and downwardly from the side walls 11 constitute a hopper with said inclined boards 13 spaced at their lower ends as at 14 to provide a discharge opening.

A regulating gate is associated with the discharge opening and comprises a pair of semi-

cylindrical gate members 15 having end walls 16 by means of which the gate members 15 are rigidly connected to a pair of shafts 17 extending longitudinally of the bucket 10 below the discharge opening in the hopper with the shafts 17 extending through and journaled in the end walls 12 of the bucket. As shown more clearly in Figure 2, the two shafts 17 are respectively journaled in the end walls 12 of the bucket at points below 10 and substantially in the vertical plane of the adjacent lower edge of the inclined board 13 with the convex sides of the gate members 15 disposed outwardly of said shafts and presented for wiping engagement with the lower edge of the 15 associated inclined board 13. When the gate members 15 are in their closed positions as illustrated in Figures 1 and 2, the chordal edges of the end walls 16 are horizontally aligned and the adjacent edges 18 of the semi-cylindrical gate 20 members 15 are engaged with each other to shut off the flow of material through the discharge opening of the hopper.

While the gate members may be moved from their opened to closed positions by hydraulic, 25 pneumatic or any mechanical means, hand-operated devices are shown merely for purposes of illustration, Figure 1 illustrating a gear 19 on each end of the two shafts 17 outwardly of the end walls 12 of the bucket 10 with the gears on 30 adjacent ends of the shafts 17 meshing with each other and located within a protective housing 20 carried by each end wall 12 of the bucket. A manually operable handle or lever 21 is fixed to one of the ends of a shaft 17 to effect simultaneous rotation of the shafts and corresponding movements of the gate members 15.

It will be observed from an inspection of Figure 2 that the convex sides of the semi-cylindrical gate members 15 are disposed upwardly and 40 presented to the discharge opening at the bottom of the hopper within the bucket. It will also be observed that the upper convex surfaces of the gate members 15 exposed to the discharge opening in the bucket are in a generally downward and central direction so that the weight of the material M in the bucket which frequently averages as high as 32,000 pounds aids in the closing movements of the gate members and definitely acts to hold the gate members in their 45 closed positions. The regulating gate members 50 are illustrated in Figure 3 as being in their opened positions with the material in the bucket passing through the discharge opening in the hopper, and it will be understood that when the gate members are moved to their closed positions, the adjacent edges 18 thereof will always travel in a downward direction toward the center of the bucket so that the weight of the material in the bucket flowing in the general direction with the closing movement of the gate members will aid the gate members in their closing movements. The gate members are free of any depressions or pockets, such as are present in the clamshell type of gate for the collection 55 of material therein with the result that the material aids in the closing movement of the gate members by flowing downwardly over the convex sides thereof. It will again be noted, as shown in Figure 2, that the weight of the material M in the bucket 10 constantly bears downwardly on the gate members to hold them in closed position.

The gate members 15 have been described in connection with Figures 1 to 3 as being of semi-cylindrical formation, but it is to be understood

that the gate members may be any segment of a circle or cam and a modified form of gate member is shown in Figure 4 wherein the arcuate gate members 15^a are less than 180°. The gate members 15^a are mounted and operated similarly to the arrangements shown in Figures 1 to 3, the gate members 15^a having the end segmental walls 16^a mounted upon shafts 17 that are connected as at 19 and operated by the handle 21. In Figure 4 it will be observed that the adjacent end meeting edges 18^a when in their closed positions are disposed above the horizontal plane of the shafts 17 so that the pocket between the adjacent portions of the semi-cylindrical gate members as shown in Figure 2 is not present. The shafts are so relatively disposed that the meeting edges 18 of the arcuate gate members 15^a move in a downward and central direction during closing movements relative to the adjacent end 14 of the inclined hopper board 13. The weight of the material in the hopper maintains the gate members 15^a in their closed positions and by the constant downward push of the material in the bucket there is a tendency for the material to close the gates when the latter are being moved to their closed positions.

In the form of invention illustrated in Figures 5 to 8, the dump bucket 25 is of the circular type and has a hopper cone 26 suitably anchored therein with a discharge opening 27 at the lower 30 end of the hopper cone 26. A pair of shafts 28 and 29 is disposed within the bucket 25 below the discharge opening 27 in the hopper cone and the ends of said shafts 28 and 29 are journaled in bearing blocks 30 carried by diametrically opposite sides of the inner face of the bucket 25. A pair of arcuate segmental gate members 31 have right angularly extending end walls 32 respectively fixed to the shafts 28 and 29 and said shafts and arcuate gate members are so 40 relatively positioned as to cause the upper convex sides of the gate members 31 to wipe the discharge opening 27 at the bottom of the cone hopper 26 to provide a valve closure therefor. The shafts 28 and 29 are interconnected by meshing gears 33 for simultaneous rotation to move the arcuate gate members 31 to their opened and closed positions relative to the discharge opening in the cone hopper.

To increase the power for the operation of the gate members 31, especially where the dump bucket handles exceptionally heavy materials, there is provided a third shaft 34 parallel with and preferably in the same horizontal plane as the shafts 28 and 29, said shaft 34 being journaled at its ends in bearings 35 carried by the inner face of the bucket 25. A pair of relatively small pinions 36 are fixed to the shaft 34 and mesh with the adjacent gears 33 on the shaft 29. The operating means for the shaft 34 and pinions 36 includes a lever or handle 37 having a forked connection 38 with the shaft 34, the handle 37 extending outwardly of the bucket 25 and vertically working through the slot 39 in the side wall of the bucket. It will be readily understood from an inspection of Figure 6 that upward movement of the handle 37 rotating the pinions 36 effects reverse rotation of the shafts 28 and 29 through the meshing gears 33 with increased leverage by the relative sizes of the gears 33 and pinions 36 so that the arcuate regulating gates 31 are comparatively easily moved in the presence of excessive weight thereon by the character of material in the hopper 26. It will also be understood that in the form of the invention

shown in Figures 5 to 8, the weight of the material in the hopper 26 constantly bears downwardly and that the meeting edges 31^a of the arcuate gates 31 travel in a downward and central direction from the hopper opening 27 of the closed positions of the gates so that the weight of the material in the hopper aids the gates in their closing movements as well as acting to maintain the gates in their closed positions.

In each form of the invention disclosed herein the weight of the material in the hopper operates to aid the regulating gates in their movements to closed positions and the weight of the material also operates to maintain the regulating gates in closed position.

From the above detailed description of the invention, it is believed that the construction and operation thereof will at once be apparent, and while there is herein shown and described the preferred embodiment thereof, it is to be understood that minor changes may be made in the details of construction, such as will fall within the scope of the invention as claimed.

25 I claim:

1. In apparatus of the character described, a bottom dump bucket having an outer casing wall open at the top and bottom thereof, a conical hopper within the outer casing wall spaced from the upper and lower ends thereof and having a bottom discharge opening, a regulating gate associated with the discharge opening at the lower end of the conical hopper within the outer casing wall above the lower end of the latter and comprising a pair of arcuate gate members having their upper convex sides movable over the discharge opening and with the meeting edges of the gate members moving in an inward and downward direction to closed abutting positions whereby the weight of the material in the bucket pressing downwardly on the gate members during closing movements is operative to aid the gate members in their closing movements and to maintain the gate members closed, the arcuate formation of the gate members being less than 180°, pivotal mountings for the gate members including a shaft journaled in the outer casing wall for the support of each gate member, gear connections between the shafts within the outer casing wall below said conical hopper, another shaft journaled at its ends in the outer casing wall and having gears thereon within said wall meshing with the gears on one of the aforesaid shafts for operating both of said shafts and said gate members.

2. In apparatus of the character described, a bottom dump bucket having an outer casing wall open at the top and bottom thereof, a conical hopper within the outer casing wall spaced from the upper and lower ends thereof and having a bottom discharge opening, a regulating gate associated with the discharge opening at the lower

end of the conical hopper within the outer casing wall above the lower end of the latter and comprising a pair of arcuate gate members having their convex sides movable over the discharge opening and with the meeting edges of the gate members moving in an inward and downward direction to closed abutting positions whereby the weight of the material in the bucket pressing downwardly on the gate members during closing movements is operative to aid the gate members 10 in their closing movements and to maintain the gate members closed, the arcuate formation of the gate members being less than 180° and having their abutting closing edges disposed in a plane above the pivotal mountings, said pivotal 15 mountings including a shaft journaled in the outer casing wall for the support of each gate member, gear connections between the shafts within the outer casing wall below said conical hopper, a third shaft journaled at its ends in 20 the outer casing wall, relatively small pinions of the third shaft within the outer casing wall meshing with the gears on one of the gate pivot shafts, the outer casing wall having a vertical slotted opening therein and a lever attached to the third 25 shaft extending through said slotted opening for effecting rotation of all of said shafts and said gate members.

3. In apparatus of the character described, a portable bottom dump bucket having an outer 30 casing wall open at the top and bottom thereof, a conical hopper within the outer casing wall spaced from the upper and lower ends thereof and having a bottom discharge opening, a regulating gate associated with the discharge opening 35 at the lower end of the conical hopper within the outer casing wall above the lower end of the latter and comprising a pair of arcuate gate members having their upper convex sides movable over the discharge opening and with the meeting edges of the gate members moving in an inward and downward direction to closed abutting positions whereby the weight of the material in the bucket pressing downwardly on the gate members during closing movements is operative to aid the 40 gate members in their closing movements and to maintain the gate members closed, the arcuate formation of the gate members being less than 180°, pivotal mountings for the gate members including a shaft journaled in the outer casing wall 45 for the support of each gate member, means within the outer casing wall forming communication between the gate members to effect simultaneous operation thereof, the outer casing wall having a vertical slotted opening therein adjacent the lower end thereof, and a hand lever operatively connected at its inner end to said gate members with the outer end of the lever extending through the slot in the outer casing wall for manual operation of the gate members. 50
